[57] CLAIM

The ornamental design for the tweezer, shown and described.

DESCRIPTION

FIG. 1 is a top plan view of a tweezer showing my new design;

FIG. 2 is a side elevational view of the tweezer;

FIG. 3 is a front elevational view of the tweezer; and
FIG. 4 is a rear elevational view of the tweezer.

The cord is omitted in FIGS. 1, 2 and 4 for ease of illustration.
